US0D1108087S

(12) United States Design Patent (10) Patent No.: US D1,108,087 S
(45) Date of Patent:  *Jan. 6, 2026

(54) COMBINED BEANIE WITH SCARF

(71) Applicant: Sumee Oy, Helsinki (FI)

(72) Inventor: Aino Elina Morimoto, Helsinki (FI)

(73) Assignee: Sumee Oy, Helsinki (FI)

(*) Notice: This patent is subject to a terminal disclaimer.

() Term: 15 Years

(21) Appl. No.: 29/781,873

(22) Filed: May 1, 2021

Related U.S. Application Data

(63) Continuation-in-part of application No. 35/507,061, filed on Feb. 6, 2019 (U.S. filing date under 35 U.S.C. 384), and having an international filing date of Feb. 6, 2019, now Pat. No. Des. 921,334.
